CARRIAGE RETURN MECHANISM FOR COMPUTING AND PRINTING MACHINES

Oscar J. Sundstrand, Bridgeport, Conn., assignor to Underwood Elliott Fisher Company, New York, N. Y., a corporation of Delaware

Original application December 18, 1931, Serial No. 581,800. Divided and this application December 31, 1936, Serial No. 118,607

6 Claims. (Cl. 197—66)

This invention relates to bookkeeping machines, and more particularly to a carriage return mechanism therefor. This application is a division of my co-pending application Serial No. 581,800, filed December 18, 1931.

5 One of the objects of the present invention is to provide a highly efficient carriage return mechanism, and one that is adapted for use in connection with bookkeeping work where it is desired at times to vary the carriage return in 10 respect to the columnar positions in which the return is begun and finished.

With these and incidental objects in view, the invention consists in certain novel features of 15 construction and combinations of parts, the essential elements of which are set forth in appended claims, and a preferred embodiment of which is hereinafter described with reference to the drawings which accompany and form part of the specification.

20 In the drawings:

Figure 1 is a plan view of the entire machine. Figure 2 is an elevation taken from the left side of the machine, and shows the gear train from the machine clutch to the carriage.

25 Figure 3 is a detail view taken on the line 3—3 of Figure 2, and looking toward the rear of the machine.

Figure 4 is a back view of the machine.

30 Figure 5 is a plan view showing the connections from the carriage return keys and the motor bar to the carriage drive.

Figures 6 to 15 inclusive are details of the carriage return mechanism.

35 Figures 16^a and 16^b, when taken together, form a perspective view of the carriage return keys and the motor bar, and their connections with the machine clutch and carriage return mechanism, and

40 Figure 17 is a perspective view showing the releasing mechanism for the latch that holds the carriage short return key in its depressed position.

General description

45 The present mechanism is shown applied to a bookkeeping machine of the ten key type provided with a travelling carriage that is tabulated from one position to another throughout its working stroke to provide for listing items in a plurality of vertical columns on a work sheet. This necessitates a movement of the carriage from right to left, as viewed from the front of the machine, and thereafter a return movement from left to right.

55 In certain types of work it is desirable not only

to return the carriage from its extreme left hand position to its extreme right hand position, but to return it from one or more intermediate positions to the extreme right hand position, or even to return it from one or more intermediate positions to another intermediate position. Such return to an intermediate position instead of to the extreme right hand position is commonly referred to as a short return or "shuttle movement." The return mechanism for the present 10 machine is provided with suitable controls to cause the return to take place automatically when the carriage is tabulated into a predetermined position and to be discontinued when it has arrived in another predetermined position. 15 Further controls are provided to cause the return mechanism to become effective in any tabular position of the carriage to return the carriage to its extreme right hand position upon depression of the key on the keyboard. There is 20 also provided an additional control to cause the return mechanism to become effective at the will of the operator to return the carriage to an intermediate tabular position by depression of another key on the keyboard. 25

Detailed description

In the present machine, the power used in returning the carriage is derived from the same motor that is used to cycle the machine. A spur gear wheel 612 (Figures 2 and 3) driven continuously during the operation of the electric motor, meshes with a spur gear wheel 885 having beveled gear teeth 886 on one side thereof that mesh with a beveled gear pinion 887, said pinion being fixed to a vertical shaft 888. A train of gears 889, 890, 891 and 892 (Figures 5 and 16^a) transmits power from the shaft 888 to a vertical shaft 893. A clutch collar 894 (see also Figures 6 to 10) is slidable but not rotatable on the shaft 893 and is adapted to engage a clutch face 895 rigid with a pinion 896. Said pinion is loose on shaft 893 and meshes with a rack bar 897 attached to the carriage. A pin 893^a (Figure 16^b) is secured in shaft 893 and extends into a slot in the lower end of collar 894 to provide the slidable and non-rotatable mounting of this collar on the shaft. 45

As is customary in machines of this character, a slippage is provided between the motor and the carriage to take the shock of starting the carriage and to prevent damage to the parts if the carriage clutch should not become disengaged when necessary. In the present mechanism this slippage is provided for by having the gear 890 (Figure 2) made of two part construction, the 50 55

upper half meshing with the pinion 889 (Figure 16^a) and the lower half meshing with the gear 891, the two halves being frictionally connected by any preferred means. When the carriage return is thrown in, slippage occurs between the two parts of the gear 890 until the inertia of the carriage is sufficiently overcome.

Manual control of carriage return

10 The means herein shown for throwing in the carriage return clutch manually at any tabular position of the carriage includes a key 898 (Figures 1, 2, 5 and 16^a) carried by a lever 899 pivoted in the machine frame at 900 (Figure 16^a).
 15 A spring 901 normally holds the key 898 elevated. The extent of downward and upward movement of such key is limited by engagement of lugs on the key lever 899 with the pivot shaft 701 (Figures 2 and 16^a). The rear end of the lever 899
 20 is arranged to lift the clutch collar 894, the washer 902 being interposed between the lever and the clutch collar. The clutch collar 894 is held in engaged position by a lever 903 (Figures 6 and 9) pivoted on a stud 904. One arm of the
 25 lever 903 has a lug 905 that lies within a peripheral groove 906 on the clutch collar. A tooth 907 is formed on the opposite end of the lever 903. A detent 908 is pivoted in the machine frame at 909 and has a tooth 910 corresponding
 30 in shape to the tooth 907. A spring 911, acting on the detent 908, holds the clutch collar in either of its two positions, and insures quick engagement and disengagement of the clutch surfaces.

35 *Disengagement of clutch*

In the return movement of the carriage, the lugs 675 (Figure 16^a) on the forward ends of the tabular stop bars 780 (Figure 1) successively pass over the upwardly extending arm of the lever 665, depressing the escapement tooth 668 on the right hand end thereof. As these stops 675 pass beyond the tooth 668 the latter springs back to its raised position where it lies in the path of these stops, a spring 674 being secured to the lever 665 for this purpose. The carriage is provided with a cam bar 912 (Figure 13) which, when the carriage approaches its initial position, engages an arm 913 formed on the lever 903, and thereby tilts said lever against the influence of the detent 908 to withdraw the clutch collar 894 from the clutch face 895. After the clutch is thus disengaged, a spring drum 643 (Figure 4) connected to the carriage by a flexible cable 644, moves the carriage to the left (Figure 16^a) a short distance, bringing the stop 675 for the first tabular position against the escapement tooth 668 to arrest the carriage in its right hand position.

80 *Automatic engagement of carriage return clutch*

A bar 914 (Figures 6, 7, 9 and 10) is mounted on the carriage to extend longitudinally thereof. The bar is attached to the carriage by headed studs 915 fixed to the bar and extending through elongated openings 916 in a member fixed to the carriage. A spring 917, attached to the bar 914 and to the carriage frame, normally holds the studs 915 against the left hand end walls of the openings 916, as shown in Figure 6. A pin 918 is mounted on bar 914 and is situated to engage the arm 913 as the carriage completes its working stroke to cause the carriage return clutch to be thrown in. The yieldable mounting of the bar 914 cushions the shock of engagement of the pin 918 with the arm 913.

Carriage short return

The carriage short return key 919 (Figures 1 and 16^a) is carried by a lever 920 secured to the shaft 701. An arm 921 is secured to the left end of this shaft. A spring 922, attached to the lever 920 and to a rod 923, normally holds the key 919 elevated; the rod 923 serving as a stop to limit upward movement of the lever 920. When the key is in its upper position, the arm 921 rests against a pin 924 on a lever 925 loosely mounted on a shaft 834. A spring 926 tends to swing the lever 925 rearwardly but is normally restrained by the arm 921. The lower end of the lever 925 has a pin and slot connection with a slide 927, the rear end of which is supported upon a guide pin 928 (see also Figure 7). A vertical slot 929 is cut in the rear end of the slide 927 to accommodate one arm of the lever 903. Lever 903 (Figures 6 and 11) is slidable on its pivot 904, making it possible for the spring 926 (Figure 16^a) to slide the lever from its normal position, shown in Figures 7 and 9, to its rear position, shown in Figures 10 and 11, upon depression of the key 919. Such shifting of the lever 903 withdraws the arm 913 from the path *x* (Figure 15) within which the clutch engaging pin 918 and the clutch disengaging cam 912 travel, and places said arm 913 in the path *y*. When in the path *y* the arm 913 will be engaged by the left hand end 930 of the bar 914, whereby the clutch will be thrown in to effect return of the carriage. A pin 931 (Figure 14), moving with the carriage, engages the arm 913 in the return travel of the carriage to disengage the clutch.

The parts 930 and 931 may be located at any desired points along the carriage so that they may initiate and interrupt movement of the carriage at any desired tabular positions. It will be understood that in both forward and rearward positions of the lever 903 the part 905 lies in the peripheral groove 906 of the clutch collar 894. At the time the short return key 919 is utilized, the carriage is standing in one of the tabular positions. The machine, therefore, must be cycled to effect tabulation of the carriage to cause the carriage to throw in the carriage return clutch—in other words, to allow the part 930 (Figure 10) to engage the arm 913. This is accomplished by throwing out the detent 576 (Figures 3 and 16^a) to allow the clutch elements 569 and 570 to engage one another and thereby cause a cycling of the machine. The means enabling depression of key 919 to throw out the detent 576 includes a pin 708 carried by an arm 707 loosely pivoted on shaft 701. A lever 709 is pivoted at 710 and has its upper arm lying beyond the pin 708. A bar 592 has an upstanding projection 711 situated in front of the lower arm of the lever 709 and extends to the front of the machine, where it is suspended on the lower arm of a lever 593 (Figure 16^b). A bar 589 has a lug 590 secured to its side and lying in front of a shoulder 591. Depression of key 919, by this train of connections, moves bars 592 and 589 forward. Movement of the bar 589 forward, through the train of connections 588, 587, 586, 585 and 584 (Figures 16^a and 16^b) causes a plate 581 to oscillate counter-clockwise about its pivot 582 against the tension of a spring 583. Since plate 581 and detent 576 are both secured to shaft 582, the movement of plate 581 will throw out the detent 576 to allow engagement of the clutch element 569 and 570 (Figure 3). The remaining details of the clutch mechanism, together with the

details of the carriage escapement, do not form a part of the present invention and are, therefore, omitted. The carriage tabulation that takes place toward the end of the ensuing cycle of the 5 machine causes the lever 903 to be rotated counter-clockwise to engage the carriage return clutch in the manner above explained.

Short return key latch

10 The lever 920 (Figure 16^a) carries a pin 932 engaging the forked end of a lever 933 pivoted on the shaft 701. A latch arm 716 is pivoted at its upper edge and has an arm extending downwardly into contact with the lower edge of a tooth on 15 the lever 933. When the key 919 is depressed, the lever 933 is swung below the arm of the latch 716, whereupon a spring 717, attached to the latch 716, pulls the latch arm rearwardly to a position immediately above the lever 933 to hold the key 20 919 depressed. In the last half of the machine cycle the key 919 is automatically unlatched by the latch 716 being moved forward against the tension of spring 717 by the following means.

A rock shaft 17 (Figure 17) is rocked first 25 clockwise and then counter-clockwise during each cycle of the machine. An arm 169 is secured to the rock shaft and carries a roller 320^c. A lever 320^b, pivoted on a rod 320^c, engages roller 320^c and carries a rod 320^a at its upper end. Actuation 30 of the rock shaft allows a suitable spring (not shown) to rock lever 320^b counter-clockwise, the rock shaft then rocking lever 320^b clockwise, moving rod 320^a first rearwardly and then forwardly in the machine. A rod 721 has pivoted thereon 35 an arm 720 having a laterally extending finger 723 adapted to contact latch 716. A pawl 718 is pivoted to arm 720 at 719 and has a notch 722 in its rear edge. When the machine is at rest, rod 320^a lies in notch 722. During the first half of 40 the machine cycle, rod 320^a is moved to the rear, whereupon pawl 718 drops until its lower edge rests on a rod 294^a. The rear edge of pawl 718 now lies in the path of rod 320^a. During the last half of the machine cycle, rod 320^a is moved forward, moving pawl 718 forward and thereby causing finger 723 to move latch 716 forward and release the depressed key 919, spring 922 returning the key to its undepressed position. Continued 45 forward movement of rod 320^a to its home position causes pawl 718 to rock clockwise, through contact of its lower edge with rod 294^a, until notch 722 falls into contact with rod 320^a, thereby allowing arm 720 to move rearwardly a short distance. This allows latch 716 to be pulled to the 50 rear under the influence of spring 717. It now lies in its normal position shown in Figures 16^a and 17 where it is effective as a latch for key 919 when the latter is depressed.

Such unlatching of the short return key occurs at about the same time in the cycle that the carriage is released for tabulation. It is, therefore, necessary to provide some means to retain the arm 913 in the path *y* until the parts 930 and 931 exercise their control on the arm 913 to produce the short return movement. As shown in 55 Figures 8 and 12, the arm of the lever 903 that is engaged by the detent 908 is rabbeted to provide two surfaces 934, thus producing locking shoulders 935 and 936. When the lever 903 is shifted 60 to its rear position, the detent 908 springs into engagement with the lower surface 934 (as shown in Figure 8), whereby the detent lies in front of the locking shoulder 935 and holds the lever 903 in its rear position after the short return key 919 65 is released by the latch 716, the releasing of the 70 75

key 919 causing a tensioning of a spring 937 (Figure 16^a) connected to lever 925 and to slide 927. The shoulder 935 thus retains the arm 913 in the path *y* long enough for the part 930 to reach and operate the arm 913 to throw in the 5 carriage return clutch. The tilting of the lever 903, as the clutch is thrown in, places the locking shoulder 936 behind the detent 910, whereby the arm 913 is retained in the path *y* and the pin 931 can reach and operate the arm 913 to disengage 10 the clutch (see Figure 14). As shown in Figure 12, the shoulder 936 is a short distance behind the shoulder 935. When the clutch is thrown in and the shoulder 936 is placed behind the detent 910, the spring 937 (Figure 16^a), being at this time 15 under tension, pulls the lever 903 forward until the shoulder 936 bears against the detent 910, this movement of the lever 903 being insufficient to withdraw the arm 913 from the path *y*. When the clutch is disengaged by the pin 931, detent 20 910 is forced from the upper surface 934 to the lower surface 907, as will be understood from Figure 12, thereby permitting spring 937 to shift the lever 903 into its normal forward position.

Time switch and its control by carriage return and short return keys

In the circuit of the motor 26 is a switch (not shown) which is arranged to be operated by means of a lever 596 (Figures 1 and 5). 30 Means is also provided for automatically opening the motor circuit after the lapse of a brief period, say, one or two minutes, following the last cycle of operations of the machine, so that in the event that the operator fails to open the 35 switch by means of the lever 596, the motor will be automatically stopped. This means comprises a switch in series with the first mentioned switch and consists of contacts 597 and 598 (Figures 5 and 16^a). The contact 598 is arranged to be withdrawn from the contact 597 by means of a lever 599 pivoted at 600. Pivoted to the lever 599 is a link 601. A cam 602 is fixed to a gear wheel 603 that meshes with a pinion 604. Fixed to the pinion 604 is a ratchet 40 wheel 605 arranged to be turned by a dog 606. A spring 607 tends to move the dog 606 in the direction to turn the ratchet wheel 605. The dog is moved in the opposite direction by means of a link 608 (Figure 16^a) which connects said 45 dog to the upper arm of a lever 609 pivoted on the axis 610. The lower arm of the lever 609 is arranged to be engaged by a pin 611 (Figure 2) carried by a gear wheel 612 rigid with the hub or tubular shaft 568 (Figure 3). The gear wheel 612 is driven continuously during the operation 50 of the motor. It will be seen that the pin 611 will oscillate the lever 609 and thus, in conjunction with the spring 607, cause the dog 606 to turn the ratchet wheel 605, thereby turning the 55 cam 602. A spring 613 connected to the link 601 tends to move said link in the direction to close the contacts 597 and 598, and also holds the link 601 in position for actuation by the cam 602. 614 is a stop pin for the link 601. On the 60 lower side of the link 601 is a stud 615 arranged at times to bear against the periphery of the cam and at other times to rest on the upper side of the cam. On the upper side of the cam is a pin 616 adapted to engage the edge 70 617 of the link 601. The end of the link 601 is arranged to be engaged by a pin 618 on the ratchet wheel 605. 619 is an anti-return dog for the ratchet wheel 605.

The link 601 is arranged to be lifted until the 75

stud 615 is above the horizontal plane of the top of the cam 602, to allow the spring 613 to move the link against the stop 614, and place the stud 615 on top of the cam. The means for lifting the link 601 comprises a slide 620 (Figure 2) the rear end of which extends through an opening 621 (Figure 3b) in a plate 622 in the machine frame. The rear end of the slide underlies the link 601. On the rear end of the slide 10 620 is an inclined surface 623 that bears against the rear end wall of the opening 621. The front end of the slide 620 is pivoted at 624 to the lever 581. When the short return key 919 is depressed, the lever 581 swings counter-clockwise, as described above, pushing the slide 620 rearwardly and raising the link 601 so as to permit the spring 613 to place the link 601 against the stop pin 614. The stud 615 then supports the link on top of the cam. The pin 616 is not of sufficient height to engage the link when the latter is thus supported. When the shoulder 625 of the cam revolves out from under the stud 615, the link 601 drops until it rests on top of the cam, the stud 615 being then alongside the low 20 part of the periphery of the cam, and the free end of the link being at the right of the orbit of the pin 618 on the ratchet wheel. As the cam continues to revolve, the pin 616 engages the edge 617 of the link 601 and swings said link 30 to the left, thus placing the free end of the link in the path of the pin 618. When the pin 618 engages the link 601, the latter is pushed rearwardly to move the contact 598 away from the contact 597, and thus open the motor circuit.

35 From the description of the above parts, it is seen that if the machine has been left idle for a sufficient length of time to allow the pin 618 to open the contacts 597 and 598, depression of the short return key 919, together with the accompanying counter-clockwise rotation of arm 581 (Figure 2) causes the link 620 to be moved to the rear and the link 601 to be raised high enough for the forward end of the link to clear the pin 618, allowing the spring 613 to close the contacts 597 and 598 to start the machine.

50 A lever 695 (Figures 2, 5 and 16a) is pivoted at 696 and has a laterally extending arm 697 underlying the carriage return key 898. A spring 901 holds the front end of the lever in its raised position. The rear end of the lever 695 has a lug 698 turned thereon and underlying the link 620. The provision of this mechanism enables a depression of the carriage return key 898 to pivot the link 620 about the connection 624, raising the rear end of the link sufficiently to raise the forward end of link 601 above the pin 618. In this manner, a depression of the Carriage return key 898, as well as the Short return key 919, closes the motor circuit if it has been previously opened by the time switch.

55 While the form of mechanism herein shown and described is admirably adapted to fulfill the objects primarily stated, it is to be understood that it is not intended to confine the invention to the one form of embodiment herein disclosed for it is susceptible of embodiment in various forms all coming within the scope of the claims which follow.

60 What is claimed is:

1. In a printing machine, the combination of a laterally movable carriage, a set of maximum-limit stops on the carriage, a set of intermediate-limit stops on the carriage, said sets of stops being located in different planes, carriage-return

mechanism including a clutch and a member adapted to engage and disengage the clutch, the member being movable into the plane of either set of limit stops, and manipulative means for adjusting the position of said member.

2. In a printing machine, the combination of a laterally movable carriage, a set of maximum-limit stops on the carriage, a set of intermediate-limit stops on the carriage, said sets of stops being located in different planes, carriage-return mechanism connectible with and disconnectible from the carriage, means movable into the plane of either set of limit stops for controlling the connection and disconnection of the carriage and the carriage return mechanism, manipulative means for adjusting the position of said controlling means, a latch to hold said manipulative means in operated position, means actuated in the cycling of the machine for moving the latch to release the manipulative means, and means to hold the controlling means in adjusted position after said latch has been released and until one of said limit stops has operated said controlling means.

3. In a printing machine, the combination of a laterally movable carriage, a clutch member for driving the carriage in the return direction, a lever connected to said clutch member to shift the same into and out of driving position, a pair of members carried by the carriage and arranged to engage an arm of said lever, one of said members engaging said arm to throw in the clutch and the other member engaging said arm to throw out the clutch, another pair of members on the carriage arranged to engage the last-mentioned arm of said lever to throw the clutch in and out, respectively, said pair of members traveling in a different path from that taken by the first-mentioned pair of members, said lever being shiftable into and out of either of said paths, and means for shifting the lever from one path to the other.

4. In a printing machine, the combination of a laterally movable carriage, a clutch member for driving the carriage in the return direction, a lever connected to said clutch member to shift the same into and out of driving position, means carried by the carriage and arranged to engage said lever to throw the clutch in and out, other means on the carriage arranged to engage said lever to throw the clutch in and out, said other means traveling in a different path from that taken by the first-mentioned means, said lever being shiftable into and out of either of said paths, manually operable means for controlling shifting of the lever from one path to the other, a spring tending to shift the lever in the opposite direction, a latch to hold said manually operable means in operated position, means actuated in the cycling of the machine for releasing the latch, and means to hold said lever in adjusted position after said latch has been released and until the lever is operated to shift the clutch element.

5. In a machine of the class described, a laterally movable paper carriage, means to limit its travel in both directions, intermediate means to limit its travel in both directions, carriage return mechanism connectible to and disconnectible from the carriage, a member pivoted on the machine for controlling the connection and disconnection of the carriage and the carriage return mechanism, said member being movable into cooperative relationship with either of said means, to be pivotally operated thereby when

the carriage is traveling in either direction, and means for so moving said member.

6. In a machine of the class described, a laterally movable paper carriage, means to limit its travel in both directions, intermediate means to limit its travel in both directions, the two means being located in different planes, carriage return mechanism connectible to and disconnectible from the carriage, a controlling member for controlling the connection and disconnection of the carriage and the carriage return mechanism, the member being movable into the plane of either of said means to cooperate therewith when the carriage is traveling in either direction, and means to move the member into the plane of either of said means. 5

OSCAR J. SUNDSTRAND.

CERTIFICATE OF CORRECTION.

Patent No. 2,216,634.

October 1, 1940.

OSCAR J. SUNDSTRAND.

It is hereby certified that error appears in the printed specification of the above numbered patent requiring correction as follows: Page 4, second column, line 4, claim 1, for the word "manipulates" read --manipulative--; and that the said Letters Patent should be read with this correction therein that the same may conform to the record of the case in the Patent Office.

Signed and sealed this 12th day of November, A. D. 1940.

(Seal)

Henry Van Arsdale,
Acting Commissioner of Patents.
